UNITED STATES PATENT OFFICE.

WALTER R. GROTJOHANN AND OSCAR D. GREEN, OF BALTIMORE, MARYLAND.

GRIP-LATCH.

1,299,460.

Specification of Letters Patent.

Patented Apr. 8, 1919.

Application filed April 6, 1916. Serial No. 89,263.

To all whom it may concern:

Be it known that we, WALTER R. GROTJOHANN and OSCAR D. GREEN, citizens of the United States of America, residing in the 5 city of Baltimore, State of Maryland, have invented certain new and useful Improvements in Grip-Latches, of which the following is a specification.

This invention relates to a fastening particularly adapted for use on windows of the type which are mounted on a horizontal pivot to swing in a vertical plane toward and from the window casing.

The handles referred to, or more properly 15 grips, may consist of a band or bar bent to form a loop preferably of a flattened semi-circular form through which the fingers and a portion of the hand are thrust in gripping. As a result of the present invention, we have 20 conceived the idea of providing in connection with such grips or handles, a latch formed integral with each handle and conveniently disengaged when the handle is seized to open or close the window and 25 spring actuated so that the window when closed is fastened as soon as the hand is taken from the handle.

In the accompanying drawings, we have 30 illustrated a swinging window to which a fastening constructed in accordance with our invention has been applied.

Figure 1 is a side elevation of a pair of sashes pivotally mounted and connected together as already described, the sash being 35 broken away for convenience in illustration:

Fig. 2 is a front elevation;

Fig. 3 is a perspective of a portion of the sash showing the right-hand grip and latch;

40 Fig. 4 is a perspective taken from the opposite side of the sash showing the left-hand grip and latch;

Fig. 5 is a view of the left-hand latch and grip detached; and

45 Fig. 6 is a section through the latch proper showing a modified form of spring attachment for actuating the latch.

Referring to the drawings by numerals, we have illustrated in Figs. 1 and 2, a pair 50 of sashes, an upper sash 1 and a lower sash 2, connected to the frame 3 at the top and bottom respectively by sliding pivots so that the bottom sash opens by swinging in at the top and rising from the bottom of the frame, 55 while the top sash opens by moving down

and swinging outward at the bottom. These two sashes are connected by a rod 4 which is pivoted centrally at 5 to the frame and pivotally connected at its ends 6 and 7 to the upper and lower sashes respectively. 60

These sashes may be secured by means of the usual window-fastening 8, 9 connecting the top of the bottom sash and the bottom of the top one, but it will be understood that owing to the particular manner of suspension, the sashes will not remain closed in the face of a strong wind unless they are fastened so that the provision of means by which they may be automatically fastened whenever they are closed and conveniently 65 released whenever it is desired to open them, is an important consideration. To this end, we have provided a snap fastening or latch 12 integral with each grip or handle 10, 11 at the left and right sides respectively, of 70 the lower sash. As we have already pointed out, the handles or grips are in the form of a looped or flattened semicircular band or bar secured to or seated at its ends in the sash, the latch or catch 12 being formed 75 integral with one of the seated ends of the loop. In the present instance, the handles or grips are in parallel vertical planes at right angles to the plane of the window and one end, preferably the lower end is mounted 80 on a pivot 13, the other end carrying the latch 12 projecting at right angles to the plane of the loop of the handle being mounted in a suitable slot 14 in the sash, or more properly a slot in the plate 15 which 85 closes the socket or chamber 16 in the sash made to receive the latch. Thus the grip is pivotally mounted to swing about its lower end in a plane parallel to the window and as it swings, the latch or catch terminal at the 90 upper end of the grip reciprocates or moves in and out through a suitable aperture 17 in the plate 15, forming the wall of the chamber 16 in the sash. The path of the latch thus described is parallel to the plane of 95 the window at right angles to the plane of the loop forming the grip and in reciprocating on this path, the latch passes in and out through the lateral surface or edge of the sash. A suitable socket 18 is provided in the 100 window frame opposite each latch in the closed position of the window and there is a spring 19 shown in Figs. 4 and 5 as a bowed or leaf spring, to impart a tendency to the latch to project from the chamber in the 105

110

sash so that when the window is closed, it will enter and remain in the registering socket in the frame.

A second form of spring believed to be 5 more durable or reliable in its action, is shown in Fig. 6 which is a cross-section through the latch and the end of the grip. In Fig. 6, we have shown the latch 12 having an internal chamber 20 elongated in the 10 direction of the latch proper, *i. e.*, parallel to the plane of the window and entering or opening at the left or inner end of the latch 12. Within the chamber 20 is a coiled helical spring 22 which may be mounted on 15 a suitable pin 23 and provided with a cup 24 adapted to slide freely in the chamber and inclose the end of the spring 22. This cup is in turn held in position by plate spring 25 which has an action supplementary to 20 the helical spring. This plate spring supports the cup 24, and holds the spiral spring 22 seated in the cup in position. It also has a supplementary action increasing the tension of the spring. This structure, as shown 25 in Fig. 6, is particularly adapted for use on steel sash windows and frames which, on account of the extra strength and cost of the material, are made of small cross-section which allows very little room for the fas- 30 tening and particularly reduces the space available for the play of the spring. By using a spiral spring such as that marked 22 in Fig. 6, instead of the leaf spring, a considerable amount of space is saved and 35 the necessity for using a leaf spring with a sharp bend which must necessarily be of short life, is avoided. The spiral spring can be furnished, particularly in the small sizes, at a comparatively low cost.

40 The operation of the latch herein described is believed to be obvious in view of the description and drawings. When the window is closed and the latches are in operation, if it should be desired to open the 45 window, the grips or handles are held one in each hand and turned inward, a comparatively slight pressure serving to overcome the springs and release the latches when the window is pulled open. If the 50 window is to be closed, the same handles are engaged and the window thrown into closed position. As the forward or inward edge of the surface of the latch is inclined at 26, Figs. 3 and 4, it is not necessary in closing 55 the window to press or swing the handles inward about their bottom ends or pivots to withdraw the latches, as this can be done by the impact of their inclined edges against the corner of the frame. But if it is de- 60 sired to close the window quietly with very little shock or jar, this can be done without greatly increased effort.

We have thus provided a convenient latch by which a swinging window of the style described, or a similar member, may be 65 closed and locked or unlocked and opened with practically no effort in addition to that now required to operate it without locking and this device is so arranged and constructed that it can be furnished at a very 70 small additional cost over that involved in supplying the handles now regarded as necessary. While we have described the latch as best adapted for use on windows of the kind illustrated in the drawings, it 75 is equally applicable for use on doors which are accessible at one side only, as doors of cupboards, refrigerators and the like.

We have thus described our invention specifically and in detail in order that its 80 nature and operation may be clearly understood; however, the specific terms herein are used descriptively rather than in their limiting sense and the scope of the invention is defined in the claims.

85 What we claim is:

1. A fastening device for windows, doors and the like, consisting of a grip and a pivot securing the same to the member to be fastened, the grip being curved forming a loop 90 substantially in a plane including the axis of the pivot, the grip having a shoulder at the end opposite the pivot, a slotted socket in the said member to be fastened, the socket containing the shouldered portion, the loop 95 passing through the slot and a latch secured to the grip adjacent the shouldered portion and projecting through the meeting surfaces of the members to be fastened, the latch moving back and forth through 100 the plane of the meeting surfaces of the two members to be fastened and at right angles to the said plane of the pivot axis and grip as the gripping member is swung back and forth about its pivot.

105 2. A fastening device for holding a swinging member in a casing, the same consisting of a grip pivoted on the swinging member to swing toward and from the edge surface of the swinging member, and a latch carried 110 by the grip and disposed at right angles to the grip and said edge surface so as to move back and forth in the direction of its length and through said plane of the edge of the swinging member as the grip swings about 115 its pivot.

Signed by us at Baltimore, Maryland, this 5th day of April, 1916.
